UNITED STATES PATENT OFFICE.

LESTER S. KEILHOLTZ, OF DAYTON, OHIO, ASSIGNOR TO DELCO-LIGHT COMPANY, OF DAYTON, OHIO, A CORPORATION OF DELAWARE.

REFRIGERATING APPARATUS.

Original application filed December 31, 1923, Serial No. 683,589. Divided and this application filed August 7, 1924. Serial No. 730,726.

This invention relates to the improvements in the construction of refrigerator cabinets especially those for mechanical refrigerators.

5 The present invention is a division of my copending application Serial No. 683,589, filed December 31, 1923.

One object of this invention is to provide a simple, quick and efficient method of assembling the cabinet.

10 Another object is to provide a water drain pipe for an upper cold compartment which does not pass through the insulated compartment below and hence provides a simpler construction.

Another object is to provide improvements in the air circulation system in the cold compartments.

Further objects and advantages of the 20 present invention will be apparent from the following description, reference being had to the accompanying drawings, wherein a preferred form of one embodiment of the present invention is clearly shown.

25 In the drawings:

Fig. 1 is a vertical section through a refrigerating cabinet embodying this invention.

30 Fig. 2 shows on an enlarged scale, the construction of the central flue shown in Fig. 1; and

Fig. 3 shows on an enlarged scale, the construction of one of the side flues shown in Fig. 1.

35 Throughout the several views like or similar reference characters refer to like or similar parts.

Numeral 20 designates the heat-insulated upper cooling compartment containing the 40 cooling unit 21; 22 is the lower heat-insulated food compartment, and 23 is the uninsulated bottom compartment adapted to contain the refrigerating machinery. Both of the heat-insulated compartments 20 and 22 45 are provided with sheet metal linings 25 and 26 respectively. These linings 25 and 26 are built up as separate unitary box-like structures having an open front.

The two separate box-like structures 50 55 and 26, with the flanged holes 31 and 32 cut therein in their bottom and top walls respectively for the air-circulation flues, are first rigidly attached to the frame of the refrigerator in a suitable manner. The holes

31 are substantially circular in shape while the holes 32 are elongated and extend substantially the entire depth of the box-like structures 25 and 26. The short metal flues 34 and 35 are next inserted in the registering holes 31 and 32 in the upper and lower 60 linings and hammered into snug engagement with the flanges thereof. Molten hydrolene or other suitable material is next applied around the outside of the flues 34 and 35 to give an absolutely air-tight sealed 65 joint between the interior of the compartments and the space outside thereof.

Elongated section-removable flues 45 telescope over the short sections 35 and are thus easily removably secured in place. The 70 flues 45 are provided at their upper end with deflectors 46 which prevent water and dirt from falling into the food compartment 22, and which are so bent as to deflect the up-flowing air along the lining 25. The 75 deflectors 46 are preferably of sheet metal and riveted or soldered to a down-turned flange on the flues 45 as clearly shown in the drawings.

Horizontal frame members 54 at the rear 80 and front of the cabinet, support the weight of cooling unit 21. Two supporting beams 55 extend across the top from members 54 and are suitably secured in slots 56 cut in said members.

85 One feature of this invention is the arrangement of the water drain pipe 40 so that it does not pass through the lower compartment 22 at all. Since the compartment 20 is maintained at a lower temperature 90 than compartment 22 and since the cold air circulates freely between these compartments through the circulation flues, the moisture in the air will be condensed out to such an extent in compartment 20 that the 95 air will be well above dew point when in compartment 22, and hence it is necessary to provide a drain pipe for compartment 20 only. Pipe 40 leads downwardly and outwardly from a point substantially at the 100 juncture of the side wall with the floor of lining 25 and thus entirely clears the lower lining 26. This is obviously a simple construction since the metal linings need be pierced and sealed at only one point. Preferably the lower portion of pipe 40 is detachable at 41 immediately under the partition 51.

The cold air circulation system and the construction of the flues is also a feature of this invention. Since the deflectors 46 deflect the up-flowing air from the food compartment 22 along the lining 25, and since the coldest part of the compartment 20 is below the cooling unit 21, the cold air will pass downwardly through the central flue 34 into compartment 22 whence it circulates and flows upwardly through the flues 45, then along the walls of lining 25 to substantially the top of the unit 24. By this means, the air from the compartment will be directed over the entire surface of cooling unit 21, and the transference of heat through the insulating walls of the cabinet will be lessened since the coldest air will not be in contact with the inner surfaces of the wall of the lining 25.

20 While the form of embodiment of the present invention as herein disclosed constitutes a preferred form, it is to be understood that other forms might be adopted,

all coming within the scope of the claims which follow.

What is claimed is as follows:

1. In a refrigerator having cooling and food compartments, linings for said compartments each having an opening, a short flue within said openings for providing an air passage between said compartments, and a relatively long flue having telescoping connection with said short flue.
2. In a refrigerator having cooling and food compartments, linings for said compartments each having an opening, insulation between said linings and having an opening, a short flue extending within the openings in said linings and providing a wall for the opening in the insulation, and a relatively long flue having telescoping connection with said short flue.

In testimony whereof I hereto affix my signature.

LESTER S. KEILHOLTZ.
